UNITED STATES PATENT OFFICE

BENJAMIN T. BROOKS, OF GREENWICH, CONNECTICUT, ASSIGNOR TO PETROLEUM
CHEMICAL CORPORATION, A CORPORATION OF DELAWARE

PROCESS FOR THE SULPHATION OF ETHYLENE AND THE SULPHATION OF A MIXTURE OF ETHYLENE AND PROPYLENE

No Drawing.

Application filed August 9, 1930. Serial No. 474,302.

This invention relates to the sulphation of ethylene or to the sulphation of a mixture of ethylene and propylene, and will be fully understood from the following description:

The ethylene to be sulphated may be obtained from any of the various sources from which ethylene is susceptible of commercial production either alone or in admixture with other hydrocarbons. The ethylene may, for example, be obtained from the destructive distillation of materials containing carbon and hydrogen, as for example in coking of coal, or may result from the cracking of natural gas, shale oil or petroleum oil.

The sulphation of ethylene, either alone or in admixture with other hydrocarbons, has been carried out by contacting the ethylene in gas phase with sulphuric acid, either fuming, anhydrous, or containing minor percentages of water. The sulphation has heretofore been carried out either at atmospheric pressure or at pressures below those hereinafter described, with the simultaneous application of acid concentration and temperature sufficient to maintain commercial reaction velocities. I have found that under the conditions heretofore employed, a substantial amount of the ethylene is degraded to polymers; and where satisfactory reaction velocities are obtained, there are ordinarily certain undesired complications, such as charring and reduction of the acid, polymerization of the hydrocarbon material to tars and heavy oils, etc.

By carrying out the reaction at higher pressure than heretofore contemplated, I am enabled to operate at lower acid concentrations and/or temperatures than have heretofore been applied in combination, and am thereby enabled not only to substantially reduce the undesirable complications hereinbefore mentioned, but also to effect substantial economies in the cost of reconcentrating the sulphuric acid employed. By the application of these pressures, I am also enabled to satisfactorily operate with gases containing rela-

tively small proportions of ethylene, which gases are too dilute in ethylene content to work satisfactorily within the range of sulphating conditions heretofore known.

The ethylene or ethylene containing gas for my purposes, may be obtained from various sources. It may, for example, be produced by cracking natural gas. It may also be the residue of non-condensable gases resulting from the coking of coal, preferably after the removal therefrom of olefines of more than 2 carbon atoms. Alternatively, the gas may be a light fraction derived from the cracking of shale oil or petroleum oil after olefines of more than 2 carbon atoms have been separated by chemical absorption, c. f., with aqueous sulphuric acid, or by selective physical absorption accomplished by contact with a hydrocarbon oil under pressure. Alternatively, the ethylene may be produced by rectification from the mixture of olefines produced by cracking shale or petroleum oils. The ethylene or ethylene containing gas may also be produced by a combination of the foregoing treatments or by any other suitable method.

In the manufacture of gasoline, for example, by cracking petroleum oils the products of cracking are ordinarily fractionated to separate therefrom gasoline and compounds of higher boiling point leaving a residue of normally gaseous hydrocarbons. This residue may be subjected to oil absorption under pressure to remove hydrocarbons of 4 or more carbon atoms leaving a residue consisting predominantly of hydrocarbons of 3 or less than 3 carbon atoms. This residue may be subjected to chemical treatment to remove the last traces of olefines of more than 2 carbon atoms leaving a mixture of hydrocarbons containing olefines of 2 carbon atoms which is suitable to my purpose. Such a mixture is preferably derived from the products of vapor phase cracking of such oils,

carried out, for example, at temperatures between 1050 and 1100° F.

The ethylene containing mixture is sulphated by contacting it with aqueous sulphuric acid under pressures in excess of 250 pounds to the square inch. The sulphuric acid should not exceed 95%, H_2SO_4 content, and the temperature should be maintained at the point at which sulphation takes place actively. I may operate with acid of from 80 to 95%, H_2SO_4 content, and at temperatures of from 30 to 125° C. Any pressure in excess of 250 pounds to the square inch may be maintained, inasmuch as the reaction is carried out in the gas phase and the temperature may be maintained above the critical temperature of ethylene.

For practical purposes, I prefer to employ a pressure in excess of 500 pounds. This may, for example, be combined with an acid concentration of from 90 to 95%, H_2SO_4 content, and a temperature of from 65 to 85° C. A temperature of 75° C. has been found quite satisfactory within this range of acid concentrations.

When operating under pressures which are adjacent the lower limit hereinbefore specified, I have obtained satisfactory reaction velocities with acid ranging from 80 to 95% at temperatures ranging from 30 to 125° C. Temperature and acid concentration are to an extent reciprocal, and for any fixed pressure and reaction velocity a lower temperature is in equilibrium with a higher acid concentration and a higher temperature with a lower acid concentration. I have, for example, obtained satisfactory reaction velocities with acid of from 90 to 95% at temperatures ranging from 30 to 95° C. Similar results have been obtained with acid of from 85 to 90%, H_2SO_4 content, at temperatures ranging from 30 to 100° C., and similar results have been obtained with acid of from 80 to 85%, H_2SO_4 content, at temperatures ranging from 30 to 125° C. When operating under pressures which are adjacent the lower limit specified, rapid reaction velocities have been obtained with acid of from 90 to 95%, H_2SO_4 content, at temperatures of from 65 to 85° C., with acid of from 85 to 90%, H_2SO_4 content, at temperatures between 80 and 100° C., and with acid of from 80 to 85%, H_2SO_4 content, at temperatures between 100 and 125° C.

By the employment of still higher pressures lower acid concentrations and temperatures may be employed in equilibrium with the practical elimination of polymerization. A pressure in excess of 500 pounds per square inch is for this reason highly advantageous, and by the application of pressures in excess of 500 pounds vigorous reaction velocities are obtainable with acid of from 80 to 90%, H_2SO_4 content, at temperatures between 30 and 50° C. The application of still higher

pressures in excess of 1000 pounds per square inch, for example, is of further advantage, inasmuch as it results in a corresponding increase of reaction rate without any substantial increase in the amount of polymerization; whereas, if the same reaction rate were obtained by increasing either the temperature or acid concentration at pressures below those herein specified, a marked polymerization loss would ensue. The application of pressures in excess of 1000 pounds per square inch is of further advantage, particularly where dialkyl sulphates are to be manufactured as hereinafter described.

The conditions heretofore employed for the sulphation of ethylene have included such a range of temperature and acid concentration as would have destroyed a substantial proportion of any propylene, if present, with the consequent loss of the propylene and with the simultaneous loss of a proportion of the ethylene in consequence of the formation of mixed polymers. By the maintenance of the conditions hereinbefore described however, I find it feasible to simultaneously sulphate both ethylene and propylene without undue loss of either component. The sulphuric acid reaction product may, if desired, be hydrolyzed to yield a mixture of ethyl and isopropyl alcohols which is susceptible of numerous valuable applications in industry. When simultaneously absorbing ethylene and propylene, I prefer to operate with a sulphuric acid containing not exceeding 90%, H_2SO_4 content, preferably of 80 to 90%, employing a temperature at which sulphation of the ethylene proceeds actively. A satisfactory temperature for this purpose is from 30 to 50° C. For maximum reaction velocities pressures in excess of 500 pounds per square inch may be employed when sulphating such a mixture of ethylene and propylene.

The sulphation reaction is preferably carried out in a column of the bubble tower type, preferably equipped with plates, bell-caps and down flow pipes, so as to maintain continuous counter-current contact of the gas and acid. I find that the bubble tower type of contactor is highly preferable to the packed tower, inasmuch as it permits the maintenance of a definite volume of acid in the tower at all times and thereby enables me to maintain any desired rate of flow of acid and gas while simultaneously permitting complete control of the time during which the materials are in contact.

It is a further advantage of my invention that by maintaining the range of conditions hereinbefore described I may either produce the mono-alkyl sulphate or may, if desired, by simply holding the acid and gas in contact for a sufficient length of time convert the same either largely or preponderantly, as desired, into the dialkyl sulphate.

When operating to produce the dialkyl sul-

phate it is essential that the sulphuric acid be present in less quantity than is theoretically required for the formation of mono-alkyl sulphates, viz, there should be less than one mol of acid for each mol of ethylene contacted therewith. For the maximum possible conversion into dialkyl sulphates there should be approximately two mols of ethylene for each mol of acid. Either the mono or dialkyl sulphate may be easily hydrolyzed to produce the alcohol therefrom; and inasmuch as one mol of the dialkyl sulphate yields two mols of alcohol, the acid consumption is sharply reduced in direct proportion to the amount of dialkyl sulphate generated. When operating with a mixture of ethylene and propylene there may be produced a mixture of simple and mixed dialkyl sulphates, depending upon which olefine is in excess. I am therefore enabled in a single state of treatment by contacting a mixture of ethylene and propylene with aqueous sulphuric acid to proceed directly to the formation of mixed alkyl sulphates. The term "mixed alkyl sulphates" as herein employed, shall denote alkyl sulphates containing in combination different alkyl radicals; and the term "simple dialkyl sulphates" shall denote dialkyl sulphates containing in combination only one type of alkyl radical.

When operating to make the mixed dialkyl sulphates, it is of course essential that the acid be present in less quantity than is theoretically necessary to the formation of mono-alkyl sulphates, viz, there should be less than one mol of acid for each unit mol fraction of ethylene and propylene contacted therewith. For maximum production of dialkyl sulphates there should be approximately one mol of acid for each unit mol fraction of ethylene and propylene contacted therewith. If the mixed olefines are not present in equimolar proportions, the olefine which is present in excess will to that extent form the corresponding simple dialkyl sulphate. Where the formation of either the simple or mixed dialkyl sulphate is desired, the acid and olefine material will ordinarily be held in contact until the acid has been predominantly converted into dialkyl sulphates. This result is expedited by the application of pressures in excess of 500 pounds per square inch, and by the application of pressures in excess of 1,000 pounds per square inch the acid may be converted almost entirely into dialkyl sulphates, even when employing acid of relatively low concentration containing, for example, from 80 to 90%, H_2SO_4 .

By operating within the range of temperatures and acid concentrations hereinbefore disclosed, and by a slight relative elevation of temperature, I find it possible to simultaneously generate a mixture of alkyl sulphate and alkyl ether. By the application

of pressure within the ranges heretofore specified, this may be accomplished with much lower concentrations of acids than would otherwise be required, thereby eliminating the undesired side reactions and concomitant production of polymers, tars, etc.; which would be inevitable under the conditions heretofore employed. The conditions may be so chosen that the ether vaporizes out of the acid liquor and is conducted away and condensed simultaneously with the progress of the sulphation reaction. The ether may also be recovered by absorption in a hydrocarbon oil, either under the operating pressure or under a higher pressure. The exact vapor pressure of the ether required for this purpose will depend upon the volume of diluent gas present, and for that reason must be selected with a view to the particular reaction mixture undergoing treatment. I have obtained satisfactory results for the simultaneous generation of ethyl sulphate and ethyl ether by operating with an acid concentration of from 90 to 95%, H_2SO_4 content, and at a temperature within the range of 100 to 130° C., while maintaining a pressure in excess of 250 pounds to the square inch and preferably in excess of 500 pounds

The term "sulphation" as employed in the description and claims shall denote the treatment with aqueous sulphuric acid resulting in the formation of either mono or dialkyl sulphates.

The foregoing description is for purposes of illustration and not of limitation, and it is therefore my intention that the invention be limited only by the appended claims or their equivalents in which I have endeavored to claim broadly all inherent novelty.

I claim:

1. Process of sulphating ethylene, which comprises contacting ethylene in gas phase with aqueous sulphuric acid of from 80 to 95%, H_2SO_4 content, under a pressure in excess of 250 pounds per square inch and at a temperature of from 30 to 125° C.

2. Process of sulphating ethylene, which comprises contacting ethylene in gas phase with aqueous sulphuric acid of from 80 to 95%, H_2SO_4 content, under a pressure in excess of 250 pounds per square inch, said acid being present in less quantity than is theoretically required for the formation of mono-ethyl sulphate and at a temperature of from 30 to 125° C., and holding the materials in contact until the acid is converted at least in part into diethyl sulphate.

3. Process of sulphating ethylene, which comprises contacting ethylene in gas phase with aqueous sulphuric acid of from 80 to 95%, H_2SO_4 content, under a pressure in excess of 500 pounds per square inch and at a temperature of from 30 to 125° C.

4. Process of sulphating ethylene, which comprises contacting ethylene in gas phase

- with aqueous sulphuric acid of from 80 to 95%, H_2SO_4 content, under a pressure in excess of 500 pounds per square inch, said acid being present in less quantity than is theoretically required for the formation of 5 mono-ethyl sulphate and at a temperature of from 30 to 125° C., and holding the materials in contact until the acid is converted at least in part into diethyl sulphate.
5. Process of simultaneously sulphating 10 ethylene and propylene, which comprises contacting a mixture of ethylene and propylene with aqueous sulphuric acid of from 80 to 90%, H_2SO_4 content, under a pressure in excess of 250 pounds per square inch at a 15 temperature of from 30 to 50° C.
6. Process of simultaneously sulphating 20 ethylene and propylene, which comprises contacting a mixture of ethylene and propylene with aqueous sulphuric acid of from 80 to 90%, H_2SO_4 content, under a pressure in excess of 250 pounds per square inch, said acid being present in less quantity than is theoretically required for the formation of 25 mono-alkyl sulphates at a temperature of from 30 to 50° C., and holding the materials in contact until the acid is converted at least in part into dialykyll sulphates.
7. Process of sulphating ethylene, which 30 comprises contacting ethylene in gas phase with aqueous sulphuric acid of from 90 to 95%, H_2SO_4 content, under a pressure in excess of 250 pounds per square inch and at a temperature of from 30 to 95° C.
8. Process of sulphating ethylene, which 35 comprises contacting ethylene in gas phase with aqueous sulphuric acid of from 85 to 90%, H_2SO_4 content, under a pressure in excess of 250 pounds per square inch and at a 40 temperature of from 80 to 100° C.
9. Process of sulphating ethylene, which 45 comprises contacting ethylene in gas phase with aqueous sulphuric acid of from 80 to 85%, H_2SO_4 content, under a pressure in excess of 250 pounds per square inch and at a 50 temperature of from 100 to 125° C.
10. Process of sulphating ethylene, which 55 comprises contacting ethylene in gas phase with aqueous sulphuric acid of from 90 to 95%, H_2SO_4 content, under a pressure in excess of 500 pounds per square inch and at a 60 temperature of from 65 to 85° C.
11. Process of sulphating ethylene, which 65 comprises contacting ethylene in gas phase with aqueous sulphuric acid of from 80 to 90%, H_2SO_4 content, under a pressure in excess of 500 pounds per square inch and at a 70 temperature of from 30 to 50° C.
13. Process of sulphating ethylene which 75 comprises contacting ethylene in gas phase with aqueous sulphuric acid of about 80%, H_2SO_4 content, under a pressure in excess of 250 pounds per square inch and at a temperature of from 100 to 125° C.
14. Process of sulphating ethylene which 80 comprises contacting ethylene with aqueous sulphuric acid of from 80 to 90%, H_2SO_4 content, under a pressure in excess of 250 pounds per square inch and at a temperature of from 30 to 125° C.
